(57) **CLAIM**

The ornamental design for a shock absorbing material, as shown and described.

DESCRIPTION

FIG. 1 is a front perspective view of a new design for a shock absorbing material;

FIG. 2 is an elevational front view thereof, the rear view being a mirror image;

FIG. 3 is an enlarged detail view thereof, taken from portion 3 of FIG. 2;

FIG. 4 is a side view thereof, the other side being a mirror image;

FIG. 5 is a top view thereof;

FIG. 6 is a bottom view thereof; and,

FIG. 7 is an enlarged detail view thereof, taken from portion 7 of FIG. 1.

The evenly spaced broken lines in FIGS. 1, 2 and 4-6 illustrate the boundaries of the claim and form no part thereof.

The dash-dot broken lines in FIGS. 1 and 2, and the evenly spaced broken lines in FIGS. 3 and 7 illustrate the boundaries of the enlarged detail views and form no part of the claimed design.

1 Claim, 6 Drawing Sheets
